UNITED STATES PATENT OFFICE.

ROBERT R. HYDE AND JOHN C. HOOK, OF SHATTUCK, OKLAHOMA.

RAILROAD TIE.

1,426,479.

Specification of Letters Patent. Patented Aug. 22, 1922.

Application filed January 28, 1922. Serial No. 532,400.

To all whom it may concern:

Be it known that we, ROBERT R. HYDE and JOHN C. HOOK, citizens of the United States, residing at Shattuck, in the county 5 of Ellis and State of Oklahoma, have invented certain new and useful Improvements in Railroad Ties, of which the following is a specification, reference being had to the accompanying drawings.

10 This invention relates to railroad ties and has for its object to provide a tie which eliminates the use of spikes by incorporating the rail fastening means in the tie.

Another object of the invention is to provide 15 a railroad tie having stationary rail engaging members or jaws disposed adjacent the ends of the tie, and movable clamping members or jaws slidably mounted on the tie.

20 It is a further object of the invention to provide a tie which is substantially hollow and having compartments formed at its ends for the reception of movable clamps or jaws, the inner wall of the compartment being 25 adapted to receive a portion of the fastening means carried by each jaw or block for urging the jaw or block toward the stationary jaw or rail engaging member.

It is still a further object of the invention 30 to provide a railroad tie wherein the upper and lower portions of the tie are open to permit the entrance of ballast and thereby prevent bending or breaking of the tie.

35 With these and other objects in view, the invention consists in the improved construction and arrangement of parts to be hereinafter more particularly described, fully claimed and illustrated in the accompanying 40 drawings, in which:—

Figure 1 is a top plan view of a railroad tie, constructed in accordance with an embodiment of the invention;

45 Figure 2 is a side elevation of the structure shown in Figure 1;

Figure 3 is a longitudinal sectional view; and

Figure 4 is a fragmentary perspective view of one end portion of the tie.

50 Referring to the drawings, 5 designates the body member or tie, including a bottom 6 and sides 7 and 8, the ends 9 and 10 of the tie being open. The bottom 6 of the tie is provided with an opening 11 which 55 permits the central portion of the tie to be positioned in accordance with the position

and pressure applied to the end portions of the tie by permitting the entrance of ballast in the body member so that breaking or bending of the tie at its central portion 60 is prevented.

The upper portion or top of the tie is substantially open, each end portion of the top being closed by a top plate 12, the purpose of which will be hereinafter described. 65 Each of the side walls 7 and 8 of the body member are provided with recesses 13, the recesses at each end portion of the side registering with the corresponding recesses in the opposite side of the body member. Each 70 of the recesses 13 has its inner wall inclined inwardly as at 14 in accordance with the shape of the base of the rail, while the wall 15 of the recess is disposed flush with the edge of the adjacent plate 12. The length 75 of the recess 13 is greater than the width of the base of a rail, so as to permit the rail to be readily inserted in the recess. To assist in bracing the rail, a rail engaging member or stationary jaw 16 is carried by the 80 upper edges of the sides 7 and 8, the edge 17 being adapted to engage the web of the rail. Disposed within the body member, between the sides 7 and 8, and engaged with the bottom 6, is a wall or partition 18 having 85 a central opening 19, the inner face of the wall being flush with the inner edge 17a of the jaw member 16, the outer face of the wall being spaced from the wall 14 of the recess 13 so as to prevent interference with 90 the rail disposed in the recess 13.

In connection with the stationary jaw or rail engaging member 16, there is provided a movable jaw member 20 consisting of a block of material of a size to fit the compartments formed in the ends of the body member, each movable jaw member being slidable in the compartments beneath the plate 12, the edge 21 of the block projecting above the base or bottom of the slots 13. Provided in 100 the end portion 22 of the block is a recess 23 which extends laterally of the end portion 22, adjacent the edge 21 of the block, the recess 23 being formed in accordance with the form of the base of the rail so that the edge 105 of said rail may snugly engage the recess. The movable jaw 22 is also provided with a longitudinally extending bore adapted to receive a bolt 24, the head of the bolt engaging the outer end portion of the block. The 110 threaded end portion 25 of the bolt is intended to pass through the opening 19 of the

wall 18, a lock washer 26 and nut 27 being threaded on the end portion 25 into engagement with the inner face of the wall 18.

In the use of the device the rail is placed 5 in the recesses 13 of the sides 7 and 8 in such a manner as to cause one portion of the base of the rail to enter the recess formed beneath the jaw member 16, the edge of the opposite portion of the base of the rail engaging the 10 wall 15 of the recess 13.

The nut 27 is then rotated by any suitable instrument to move the movable jaw member longitudinally of the tie, so as to position the last mentioned edge of the rail within 15 the recess 23. Continued movement of the movable jaw 20 will cause the rail to be firmly clamped by urging the rail into engagement with the wall 14 of the recess.

From the foregoing it will be readily seen 20 that this invention provides a novel form of railroad tie which firmly clamps the rail without the use of spikes, in addition to preventing spreading of the rails by side pressure of the train, as the bolts are not connected to the extremity of the end portions of the tie, but are substantially held by the stationary wall 18 so that any strain upon the jaw member 20 will be distributed to the wall 18 through the medium of the bolt. 25 Furthermore, as the bolt does not engage the rail, there is no danger of vibration causing accidental movement of the jaw 20 and as the jaw is slidable within the compartment formed in the ends of the tie, lateral movement is prevented and the jaw at the same time is protected from contact with any object. In addition to this, by the use of a solid block in the construction of the movable jaw, the weight of the rail is supported 40 the same as if the end portions of the tie were solid. Another important feature of this tie is that it is composed of only three parts, namely, the body member which includes the stationary jaw member 16, and the movable jaws 20. It will also be noted that the fastening means for each movable jaw is independent of the fastening means of the oppo- 45

site movable jaw, so that said jaws may be adjusted independently of each other to permit removal of one rail without disturbing 50 the opposite rail, and as the simplicity of the tie renders the same substantial, it will last indefinitely.

What is claimed is:—

1. A railroad tie of the character described 55 comprising a body member including a bottom and side walls, the ends of the body member being open, plates carried by the top of the end portions of the body member, walls disposed inwardly of the ends of the tie in 60 spaced relation to said plates, said walls co-operating with the plates to provide compartments in the end portions of the tie, the side walls of the body member being provided with rail slots, said rail slots being disposed adjacent the walls of the compartments, a jaw member extending from the side portions of the body member and connected to the wall of each compartment, a movable jaw member slidable within the compartment beneath the plate, and a bolt carried by the movable jaw and movable through the inner wall of the compartment for urging the movable jaw into engagement with the rail. 65

2. A railroad tie of the character described 75 comprising a body member including a bottom and side walls, said bottom having a relatively large opening in its central portion to permit the entrance of ballast, the ends and top portion of the tie being open, a 80 stationary jaw member carried by the upper edges of the side walls adjacent each end of the tie, plates carried by the end portions of the tie in spaced relation to the stationary jaw members, walls disposed beneath the stationary jaw members in spaced relation to the edge of the opening in the bottom of the tie, and a movable jaw member slidable within each end portion of the tie between the wall and the extremity of said end portion. 90

In testimony whereof we hereunto affix our signatures.

ROBERT R. HYDE.
JOHN C. HOOK.
